UNITED STATES PATENT OFFICE

CLIFFORD E. HARRISON, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA

FRONT WALL AIR GRID

Application filed October 2, 1929. Serial No. 396,751.

This invention relates to furnace wall constructions and more particularly to the construction of the base of a front furnace wall.

5 An important object of the invention is the provision of a structure of this character which provides for air-cooling of the front wall and at the same time produces a flat surface upon which the wall may be 10 built.

A further object of the invention is the production of a construction such that front grid bars associated with the cooled section of the wall are made removable and are so 15 constructed that they may be held in position without the use of bolts or the like and may, accordingly, be readily replaced whenever this becomes necessary without disturbing the brick work of the wall.

20 A still further object of the invention is to provide an air-cooled extension for the usual ram box cap which combines with the air boxes of the cooled wall structure to form a seat for the brick work of the wall 25 and is so formed that it may be removed and replaced without damage to the brick work.

A further object of the invention is the 30 production of a construction of the character above described which may be practically produced, which is readily installed, and which will be durable and efficient in service.

35 These and other objects I attain through the construction shown in the accompanying drawings wherein, for the purpose of illustration, I have shown a preferred embodiment of my invention and wherein:

40 Fig. 1 is a fragmentary perspective of the air-cooled section, parts being broken away to show the method of connecting the air boxes and ram cap extensions to the normal furnace structure;

45 Fig. 2 is a vertical sectional view through

the air box and its associated removable grid bar structure;

Fig. 3 is a vertical sectional view through the ram cap and its extension;

Fig. 4 is a fragmentary inner face view of 50 a furnace front wall constructed in accordance with my invention; and

Fig. 5 is a section on line 5—5 of Fig. 4.

Referring now more particularly to the drawings, the numeral 10 generally designates side plates of a retort and 11 a side plate cap comprising a plate horizontally disposed and maintained in this position through angular side flanges 12 engaging the inclined upper edges of the retort side 55 plates. This plate has an opening therethrough permitting passage of air from the spaces between the retort side plates and at its upper surface is formed with a plurality of lugs 13 co-acting with an air box 14 to 60 maintain the same against dislodgment upon the upper surface of the plate and to maintain an opening 15 formed in the bottom wall 16 of the box in alignment with the opening 17 of the plate. The outer wall of 70 this box is closed as indicated at 18 while the inner end thereof opens to the interior of the furnace. Upon the side walls of the box adjacent the inner end thereof substantially C shaped flanges 19 form recesses 20 75 the inner ends of which are open. These recesses are in communication with the interior of the box through an opening or openings as indicated at 21. Extending transversely of the box adjacent the inner 80 end thereof and projecting through the side walls into the recesses is a bar 22, the purpose of which will presently appear.

The front edges of the side walls of the box are cut away below the upper wall 23 85 as indicated at 24 so that at the inner end of the box the inner edge of the side plate cap 11 is exposed for a substantial distance. Grid bars 25 are provided, each comprising a body of uniform thickness, the side edges 90

- of which are formed with parallel horizontally extending grooves 26 producing air openings 27 when the bars are in side to side relation. The lower ends of these bars seat 5 upon projecting inner edges of the side plate cap and the upper ends of the bars which are reduced in depth as indicated at 28 abut against the upper wall 23 of the box. This upper wall at its inner edge is thickened 10 at 29 and the upper extremities of the bars engage thereagainst in such manner that the upper faces are spaced below the level 15 of the upper face of the air box upper wall 23.
- 15 Projecting inwardly from the inner face of each grid bar is a cooling flange 30 which, adjacent its upper end, is provided with a hook 31 having a downwardly projecting bill adapted to engage against bar 22. Bar 20 22 is canted so that its inner face 32 inclines inwardly and downwardly with the result that the bill of hook 31 engaging thereagainst wedges the grid bar inwardly so that it is firmly held against the inner face of 25 the air box.
- About the opening 15 the air box is preferably provided at its under surface with an annular packing-receiving groove 15-a for the reception of a ring of packing pre- 30 venting escape of air between the air box and the side plate cap. The air box is provided in its lower wall 16 with a bolt opening 16-a through which a bolt may be directed for passage through the said plate 35 cap and the uppermost tuyere "T" which projects thereunder as indicated in dotted lines in Fig. 2.
- Ram box cap extension 33 is in the form 40 of a hollow metallic block having openings 34 through its inner end wall 35 and openings 36 through its side walls and at its under surface, at the sides thereof, is provided with downwardly projecting flanges 37 adapted to seat upon the edges of adjacent 45 side plate caps 11. At its front wall the block is provided with hooked extensions 38 adapted to engage through openings 39, formed in the upper surface of the ram box cap 40, and over the front wall 41 of this 50 cap. It will be noted that the sides of the extensions 33 abut the outer edges of the flanges 19 and that the openings 36 communicate with the recesses 20 formed upon the sides of the air boxes 14 so that air 55 passing from the air boxes through openings 21 may enter the ram cap box extension and escape therefrom through openings 34. In erecting a furnace wall with a construction of this character, bricks "B" are placed upon 60 the upper surface of the ram box cap and ram box cap extension to fill the space therebetween, crevices being suitably filled with fire clay or some suitable substance. The 65 bricks B also abut the outer edges of the flanges 19, the latter functioning to space the bricks as well as the cap extensions 33 from the side walls of the air boxes and providing spaces for insertion of the end grid bars of each box. This brick work will combine with the tops of the air boxes to 70 provide a smooth even surface upon which the wall "W" may be erected. It will be noted that the inner face of this wall will project slightly beyond the inner edges of the air boxes 14 and will accordingly overhang the upper ends of grid bars 25. Fire clay or some suitable filler of the same character as indicated at 42 is placed between the projecting edge of the wall "W" and the upper end faces of the grid bars and 75 serves to effectually prevent any vertical movement of the grid bars. In the event these bars become burned or broken and must be replaced this may readily be accomplished by digging out the filling 42 and elevating 80 the bars so that the bills of hooks 31 clear the wedge bars 22 when they may be removed in a horizontal direction. In event that ram box cap extension must be replaced, brick work "B" is removed which 85 may be accomplished without disturbing the wall "W".
- As the structure employed is obviously capable of a considerable range of change and modification without in any manner departing from the spirit of my invention I 90 accordingly do not limit myself to such structure except as hereinafter claimed.
- I claim:
1. In a stoker furnace including spaced retorts, a support for the front wall there-of including ram box caps associated with the retorts and air boxes disposed between the ram box caps and communicating with the spaces between the retorts, said air boxes each having a plurality of independently removable grid bars at their inner ends, the rear ends of the air boxes extending rearwardly of the ram box caps and extensions for said ram box caps which are hollow and in communication with the air boxes, said ram box cap extensions having openings at their rear ends. 100
  2. In a stoker furnace including spaced retorts, a support for the front wall there-of including ram box caps associated with the retorts and air boxes disposed between the ram box caps and communicating with the spaces between the retorts, said air boxes each having a plurality of independently removable grid bars at their inner ends, the rear ends of the air boxes extending rearwardly of the ram box caps and extensions for said ram box caps which are hollow and in communication with the air boxes, said ram box cap extensions having openings at their rear ends, connections for said caps and their extensions disengageable by vertical movement of said extensions, removable means seated upon the caps and their 105
  3. In a stoker furnace including spaced retorts, a support for the front wall there-of including ram box caps associated with the retorts and air boxes disposed between the ram box caps and communicating with the spaces between the retorts, said air boxes each having a plurality of independently removable grid bars at their inner ends, the rear ends of the air boxes extending rearwardly of the ram box caps and extensions for said ram box caps which are hollow and in communication with the air boxes, said ram box cap extensions having openings at their rear ends, connections for said caps and their extensions disengageable by vertical movement of said extensions, removable means seated upon the caps and their 110
  4. In a stoker furnace including spaced retorts, a support for the front wall there-of including ram box caps associated with the retorts and air boxes disposed between the ram box caps and communicating with the spaces between the retorts, said air boxes each having a plurality of independently removable grid bars at their inner ends, the rear ends of the air boxes extending rearwardly of the ram box caps and extensions for said ram box caps which are hollow and in communication with the air boxes, said ram box cap extensions having openings at their rear ends, connections for said caps and their extensions disengageable by vertical movement of said extensions, removable means seated upon the caps and their 115
  5. In a stoker furnace including spaced retorts, a support for the front wall there-of including ram box caps associated with the retorts and air boxes disposed between the ram box caps and communicating with the spaces between the retorts, said air boxes each having a plurality of independently removable grid bars at their inner ends, the rear ends of the air boxes extending rearwardly of the ram box caps and extensions for said ram box caps which are hollow and in communication with the air boxes, said ram box cap extensions having openings at their rear ends, connections for said caps and their extensions disengageable by vertical movement of said extensions, removable means seated upon the caps and their 120
  6. In a stoker furnace including spaced retorts, a support for the front wall there-of including ram box caps associated with the retorts and air boxes disposed between the ram box caps and communicating with the spaces between the retorts, said air boxes each having a plurality of independently removable grid bars at their inner ends, the rear ends of the air boxes extending rearwardly of the ram box caps and extensions for said ram box caps which are hollow and in communication with the air boxes, said ram box cap extensions having openings at their rear ends, connections for said caps and their extensions disengageable by vertical movement of said extensions, removable means seated upon the caps and their 125
  7. In a stoker furnace including spaced retorts, a support for the front wall there-of including ram box caps associated with the retorts and air boxes disposed between the ram box caps and communicating with the spaces between the retorts, said air boxes each having a plurality of independently removable grid bars at their inner ends, the rear ends of the air boxes extending rearwardly of the ram box caps and extensions for said ram box caps which are hollow and in communication with the air boxes, said ram box cap extensions having openings at their rear ends, connections for said caps and their extensions disengageable by vertical movement of said extensions, removable means seated upon the caps and their 130

extensions filling the space between the air boxes and normally preventing removal of the extensions and a wall supported from said removable means and said air boxes.

6. 3. In a stoker furnace including spaced retorts, a support for the front wall thereof of including ram box caps associated with the retorts and air boxes disposed between the ram box caps and communicating with the spaces between the retorts, the rear ends of the air boxes extending rearwardly of the ram box caps and extensions for said ram box caps which are hollow and in communication with the air boxes, said ram box cap extensions having openings at their rear ends, connections for said caps and their extensions disengageable by vertical movement of said extensions, removable means seated upon the caps and their extensions filling the space between the air boxes and normally preventing removal of the extensions and a wall supported from said removable means and said air boxes.

25. 4. In combination with a stoker furnace having the usual retort side plates, the upper ends of which in alignment with the retorts are bridged by ram box caps, air boxes supported from said side plates intermediate the ram box caps and having their inner ends open and removable grids at the inner ends of said boxes, said boxes and the ram box caps forming a support for the front wall of the furnace.

5. A furnace front wall support comprising ram box caps alternated with air boxes, the air boxes having removable grids at their inner ends, said air boxes projecting rearwardly beyond the inner ends of the air box caps, hollow extensions for said ram box caps having apertures in their inner end walls and means for delivering air to the air boxes and to the interior of said extensions.

6. A furnace front wall support comprising ram box caps alternated with air boxes, the air boxes having removable grids at their inner ends, said air boxes projecting rearwardly beyond the inner ends of the air box caps, hollow extensions for said ram box caps having apertures in their inner end walls and means for delivering air to the air boxes and to the interior of said extensions through said air boxes.

7. An air box for stoker furnaces comprising a casing having an inlet opening and an open side, a bar paralleling said side and having the face thereof removed from the wall inclined and grid bars for bridging the said side having hooks the bills of which have wedging engagement with said bar to thereby maintain said bars in engagement with the upper and lower walls of the casing.

8. An air box for stoker furnaces comprising a casing having an air inlet and an

open side, grid bars for disposition at said open side and co-acting to form a grid thereon and co-acting means upon said grid bars and casing for wedging the bars inwardly against the upper and lower walls of the casing.

9. An air box for stoker furnaces comprising a casing having an air inlet and an open side, grid bars for disposition at said open side and co-acting to form a grid thereon and co-acting means upon said grid bars and casing for wedging the bars inwardly against the upper and lower walls of the casing, disengageable to permit horizontal removal of the grid bars after a predetermined vertical movement thereof.

10. A furnace front wall support comprising ram box caps alternated with air boxes, the air boxes having removable grids at their inner ends, said air boxes projecting rearwardly beyond the inner ends of the air box caps, hollow extensions for said ram box caps having apertures in their inner end walls and means for delivering air to the air boxes and said extensions having communication through confronting walls thereof.

11. A stoker furnace comprising alternately arranged inclined retort and tuyère sections, horizontally arranged plates supported at the upper ends of the said tuyère sections, air boxes mounted on said plates, the plates being apertured to afford communication between the interiors of the tuyères and said boxes, ram box caps bearing upon said plates in positions intermediate said air boxes and bridging the upper ends of the retorts, and hollow cap extensions also positioned on said plates intermediate the air boxes, said extensions and air boxes having apertures through which communication is established between the interiors of the extensions and the air boxes, and said extensions having discharge openings communicating with the space overlying said retorts.

12. In a stoker furnace, the combination with alternately arranged inclined retort and tuyère sections, of plates horizontally disposed at the upper ends of the said tuyères, air boxes mounted on said plates, interlocking means for predeterminedly positioning said air boxes on the plates, said plates having apertures through which the interiors of said boxes communicate with the interiors of tuyères, and said air boxes having discharge openings communicating with the space overlying the said retorts and tuyères, and ram box caps mounted intermediate the air boxes in positions bridging the upper ends of the retorts, each of said caps comprising a hollow section having apertures communicating with the space overlying the said retorts and tuyères, and said hollow sections and said air boxes having related apertures through which com-

munication is established between the interiors of the said hollow sections and the interiors of said boxes.

13. In a stoker furnace, the combination with alternately arranged inclined retort and tuyère sections, of plates mounted in horizontal positions at the upper ends of said tuyères, separately formed air boxes and ram box caps supported on said plates 10 in alternate arrangement with the said caps bridging the upper ends of the retorts, said air boxes and caps being hollow and having apertures through which their interiors communicate, and said plates having apertures 15 through which the interiors of said boxes communicate with the interiors of the tuyères, both the caps and air boxes having discharge ports communicating with the space overlying the said tuyères and retorts.
14. In a stoker furnace, the combination with alternately arranged inclined retort and tuyère sections, of plates secured in horizontal position at the upper ends of the tuyère sections, each of said plates having 20 an aperture communicating with the interior of the underlying tuyère, independently formed ram box caps and air boxes mounted above said plates, means interlocking the plates with the said caps and air boxes 25 whereby the caps and air boxes are predeterminedly positioned, said caps and air boxes being hollow and having related apertures establishing communication between the interiors, and said boxes communicating 30 with the tuyères through the said apertures in the plates, both the said caps and air boxes having discharge openings communicating with the space overlying the retorts and tuyères.
15. In a stoker furnace, the combination with an inclined grate structure comprising alternately arranged retort and tuyère sections, of a plate secured in horizontal position at the upper end of each of said tuyères, 35 independently formed ram caps and air boxes supported on said plates in alternate arrangement, and means on said plates interlocking both with the ram caps and with the air boxes for maintaining said caps and 40 boxes in predetermined positions.

16. In a stoker furnace, the combination with an inclined grate structure comprising alternately arranged retort and tuyère sections, of a plate secured in horizontal position at the upper end of each of the tuyères, 45 an air box mounted on each of said plates and communicating through the plate with the interior of the underlying tuyère, said air box having apertures communicating 50 with the space overlying the grate, and hollow ram cap elements also supported on said plate in positions bridging the upper ends of the retorts and communicating with the interiors of said air boxes, said cap elements having discharge openings communicat-

cating with the space above the said grate.

17. A furnace front wall support comprising alternately arranged ram box caps and air boxes, said caps having removable box-like inner end portions communicating with the interior of adjoining boxes and apertured at their inner ends, and said boxes having at their inner ends removable grids, and interlocking means securing the portions of the respective caps together. 70

18. In a stoker furnace including spaced retorts, a support for the front wall thereof including ram box caps associated with the retorts, and air boxes disposed between the ram box caps and communicating with the spaces between the retorts, said caps having removable box-like inner end portions communicating with the interior of adjoining boxes and apertured at their inner ends, and said boxes having at their inner ends removable grids. 80

19. A furnace front wall support comprising independent alternately arranged ram box caps and air boxes, said caps comprising inner box-like portions communicating with the interior of adjoining boxes, and said boxes and the box-like portions of said caps being apertured at their inner ends. 90

20. In a stoker furnace including spaced retorts, a support for the front wall thereof including ram box caps associated with the retorts, and air boxes disposed between the ram box caps and communicating with the spaces between the retorts, said caps having inner box-like portions communicating with the interior of adjoining boxes, and both the boxes and said box-like portions being apertured at their inner ends. 100

21. A grid for an air-cooled furnace wall comprising a body portion having a surface exposed to the heat of the furnace, said body portion being substantially uniform in width, the upper and lower ends thereof being relatively thick and tapering toward the exposed surface of said body portion so that a substantial portion thereof intermediate said end is relatively thin, a series of parallel grooves provided along the sides of said body portion, a flange extending rearwardly of said body portion and positioned intermediate the side edges thereof, and a hook provided at the rear end of said flange for engaging fixed securing means to retain said grid in proper position. 110

22. A grid for an air-cooled furnace wall comprising a body portion having a surface exposed to the heat of the furnace, said body portion being substantially uniform in width, the upper and lower ends thereof being relatively thick and tapering toward the exposed surface of said body portion so that a substantial portion thereof intermediate said ends is relatively thin, a series of parallel grooves provided along the sides of said body portion, a flange extending rearward- 120

125

130

ly of said body portion and positioned intermediate the side edges thereof, the upper and lower edges of said flange terminating inwardly of the ends of said body portion to facilitate the installation and removal of said grid, and a hook provided at the rear edge of said flange for engaging fixed securing means to retain said grid in proper position.

10 23. A grid for an air-cooled furnace wall comprising a body portion having a surface exposed to the heat of the furnace, the lower end of said body portion being relatively thick to provide an extended base, a series 15 of parallel grooves provided at the sides of said body portion, and a flange extending rearwardly of said body portion intermediate the side edges thereof, said flange constituting means for securing said body portion to a supporting structure.

20 24. A grid for an air-cooled furnace wall comprising a body portion having a surface exposed to the heat of the furnace, said body portion being relatively thin over the major portion of its length but being extended rearwardly at the bottom to form a substantial base, a flange extending rearwardly from said body portion intermediate the side edges thereof, and means on said flange providing for interlocking engagement thereof with a supporting structure, said body portion having at its longitudinal edges a series of grooves forming air channels terminating at opposite ends in the front and rear 25 faces respectively.

30 25. A ram box cap extension of substantially inverted U-shaped form, the upper portion of said cap extension being provided with an air chamber and a reduced portion 35 extending to the rear thereof, a hook provided on said reduced portion for engaging fixed securing means to retain said cap extension in proper position, an enlarged air passage provided at each side of said cap extension and leading to said chamber, and a series of air passages leading from said chamber to the front surface of said cap extension, said parts being so arranged that air may enter said chamber through said 40 first-mentioned passages and be discharged through said last-mentioned passages.

45 26. A ram box cap extension of substantially inverted U-shaped form, the upper portion of said cap being provided with an air chamber, the upper wall of said chamber, forming the upper surface of said extension, and the lower wall of said chamber converging with said upper wall toward the inner end of said extension, said extension 50 having at a side thereof an air passage communicating with said chamber and having a series of air passages extending from said chamber to the inner surface of said extension.

55 27. An air box for stoker furnaces com-

prising a casing having an air inlet and an open side, the upper edge of said open side projecting beyond the lower edge, grid bars for disposition at said open side and co-acting to form a grid thereon, and means for supporting said bars against said upper and lower edges, said bars being of greater thickness at the bottom than at the top whereby the outer faces of said bars occupy a substantially vertical plane.
